UNITED STATES PATENT OFFICE

DANIEL SMITH, OF WOLVERHAMPTON, ENGLAND

STRIP-METAL-BENDING MACHINE

Application filed March 7, 1929, Serial No. 345,085, and in Great Britain March 8, 1928.

This invention relates to machines for shaping strips of metal to any suitable cross-section and for bending the same into a circular or coiled configuration; and is particularly applicable in connection with the production of the rims of motor vehicle hand steering wheels and tubular coils.

According to the present improvements, a strip of metal is passed through means for shaping the same into a suitable cross-section, to a coiling device which pulls the strip of metal through the said shaping means. The coiling device comprises a quadrant or like member having a circular or other circumference and the strip of metal after leaving the said shaping tools is gripped on the quadrant so that the rotation of the quadrant bends the strip round its periphery or circumference, whilst also pulling the same through the cross-sectional shaping tools. In the case of a tubular or similar shaped member the metal is stretched on the outer side so that its shape will not be damaged as it is bent round the quadrant or like coiling member. The quadrant is oscillated and the gripping means are released on the backward movement and applied on the forward or feed movement. A coiled length of tubing or other shaped strip of the required cross-sectional shape is thus produced from which lengths are cut to form the rim of the wheel or other circular or other form of spiral article.

Referring to the drawings:—

Figure 1 is a side elevation of a machine constructed according to this invention,

Figure 2 is an end view,

Figure 3 is a plan,

Figures 4, 5 and 6 are sections through the tube shaping rolls,

Figure 7 is a side elevation of the means for driving the rolls, and

Figure 8 is a plan view of the parts shown by Figure 7.

According to a convenient embodiment, the invention is applied to the production of rims for the steering wheels of motor vehicles. The machine comprises a frame A in which are mounted two pairs of spindles, each pair of which are geared together respectively by

the pairs of gear wheels 1^a, 1^b, and 3^a, 3^b. Rolls are mounted on the ends of the spindles projecting from the front face of the frame, the first and second pairs of rolls being numbered respectively 1 and 3. An intermediate bottom roll 2 is also provided. A mandrel 4 passes between the rolls. A flat strip of metal is fed through the machine and the first pair of rolls 1, as shown by Figure 4, give a preliminary curl to the strip of metal. The second bottom roll, as shown by Figure 5, further curls the metal around the mandrel 4 which is shaped as shown by Figure 5, the flat portion opposite the roller 2 allowing the metal to curl thereover, and a lubricator 2^b being adapted to intermittently drop oil on the metal strip at this operation. The third pair of rolls 3 applies the finish to the cross sectional shape. The cross sectional shape of the rim of the wheel may for instance be oval, with the major axis lying parallel to the plane of the wheel and with the joint on the inside. The joint may be on the outside in the case of some gauges of metal. A mandrel 4 passes through the shaping tools and the metal strip is bent therearound. A quadrant 5 is fixed to the shaft 6 and has a groove 7 in the periphery adapted to receive the shaped strip of metal. A clamp 8 is adapted to bind the metal on the quadrant 5 so that when the quadrant is rotated, the metal is pulled through the aforementioned rolls. The clamping member has a groove 9 therein shaped to receive the metal strip so that the groove in the quadrant and the groove in the clamp are of a similar shape to the rim of the wheel. The quadrant has two arms 10 projecting radially therefrom between which the clamp is located and slidably mounted thereon in the slots 11. A link 12 is pivotally connected to the lower end of these arms 10 and such link is jointed to a connecting rod 13 driven by the disc 14. The upper end of the link 12 is extended beyond the joint to the arms 10 carried by the quadrant, and this extended end is connected by a link 15 to the clamp. The quadrant therefore is oscillated and on the coiling or power stroke the clamp 8 is forced into the gripping position by means of the toggle link arrangement

100

aforedescribed. On the return stroke however the clamp 8 is pulled away from the quadrant so that the quadrant and clamp freely slide over the shaped tube. The spindle 16 jointing the upper end of the link 12 to the arms 10 carried by the quadrant has an eccentric centre portion 17 which engages a hole in the link 12 in order to adjust the setting of the clamp, and the spindle is conveniently held in the desired position of adjustment by means of a ring which is fixed to the spindle 16 and has a number of perforations therearound so that any one of the holes may be pinned to one of the arms 10. The connecting rod 13 operating the quadrant is mounted in a block 18 adjustable in a radial slot in the gear wheel 14 mounted on the stub axle 19. The gear wheel 14 is driven by the gear wheel 20 mounted on the shaft 21, which carries the gear wheel 22 meshing with the gear wheel 23 on the belt pulley shaft. The spindle 6 on which the quadrant 5 is mounted is also carried by an adjustable bearing block, to provide for the fitting of various sized quadrants in accordance with the curvature or form to which the tube is to be bent. The three bending rolls 1, 2 and 3 are driven during the feed or power stroke of the quadrant, and for this purpose the roll spindles are driven by a chain 24 which engages over sprocket wheels mounted on the spindles of the bottom roll of the pairs 1 and 3. A bar 25 is adapted to rest on the upper run of this chain, and such bar carries a pivoted pawl 26 for engaging between the links of the chain. The end of this bar is coupled by an adjustable link 27 to an arm 28 mounted on the quadrant spindle 6. The length of this arm is in accordance with the radius of the quadrant 5. When therefore the quadrant 5 is moving on the power stroke, the pawl 26 engages the chain and positively rotates the rolls. On the return stroke the pawl rides over the chain. The pawl 26 aforementioned is mounted in a slot in the comparatively heavy bar 25 so that the arrangement is maintained steady, and there will be no liability of the pawl becoming disengaged during the driving stroke. The gear wheels 3^b and 2 are geared together by the gear wheel 29 and the wheels 2 and 1^b are geared together by the wheel 30.

The mandrel projects beyond the third pair of rolls and slightly beyond the vertical line passing from the axis of the quadrant 5. When therefore the metal strip is gripped on the quadrant and pulled therearound, the outer side of the tube pulling over the end of the mandrel is stretched to allow for the increased length at the outer periphery, thereby ensuring that the rim will have a perfectly smooth surface. The coiled tube is passed over the bar 34.

The machine thus shapes a flat strip of metal into a tube and afterwards bends the

tube into a predetermined form or curvature. The tube is thus bent continuously into a circular configuration, and therefore assumes the shape of a close coiled tube; a length of tube corresponding to one complete turn, can be cut off the coil and the ends joined together to form the rim of a steering wheel or the like. 70

The quadrant 5 has a guide member 31, having the guide opening 32, fixed thereon to guide the tube on to the quadrant. A bracket 33 may also be provided to support the portion of the mandrel 4 projecting beyond the rollers 3. The means for shaping the strip into tube or other cross section 80 may be considerably modified. 75

While the invention has been particularly described to produce circular coils, the coiling device may be arranged to form other than circular coils, for instance the shape 85 of each turn may be of a square configuration with the corners rounded. 85

Claims:

1. Means for shaping a strip of metal into tubular form in cross-section comprising 90 shaping rolls, and a mandrel over which the tube is shaped, in combination with means for coiling or bending the tube thus formed comprising a quadrant or member, means for oscillating said member, and means for automatically gripping the tube to said member on the working stroke which gripping means are automatically released on the return stroke, and means for stretching the tube on its outer side as it passes on to the quadrant comprising the end of the said mandrel over which the end of the tube is pulled. 100

2. Means for shaping a strip of metal into tubular form in cross-section comprising 105 shaping rolls in combination with means for coiling the tube thus formed comprising a quadrant, means for oscillating said quadrant, means for automatically gripping the tube to said member on the working stroke 110 for pulling the tube therearound which gripping means are automatically released on the return stroke, and means for intermittently driving the said shaping rolls on the working stroke of the quadrant through the medium of mechanism oscillating with the quadrant. 115

3. Means for shaping a strip of metal into tubular form in cross-section comprising 120 shaping rolls in combination with means for coiling the tube thus formed comprising a quadrant, means for oscillating said quadrant, means for automatically gripping the tube to said member on the working stroke 125 for pulling the tube therearound which gripping means are automatically released on the return stroke, and means for intermittently driving the said shaping rolls on the working stroke of the quadrant comprising a chain 130 passing over sprockets mounted on spindles

carrying the shaping rolls, a bar resting on the chain and having a pawl for engaging the links of the chain, and an arm oscillating with the said quadrant and connected to the bar.

5. Means for shaping a strip of metal into a suitable cross-section, in combination with means for coiling the tube thus formed, comprising a quadrant, a connecting rod for oscillating the quadrant, arms fixed to the quadrant and coupled to the end of the connecting rod by a connecting link, a gripping device slidably mounted in the arms fixed to the quadrant, and a toggle link connected to the gripping device and said connecting link.

10. Means for shaping a strip of metal into a suitable cross-section, in combination with means for coiling or bending the tube thus formed comprising a quadrant, means for gripping the strip on the quadrant during the working stroke, means for oscillating the gripping means to bend the shaped strip lengthwise, and means driven from the quadrant for drawing the strip of metal through the means for shaping the strip into suitable cross-section.

In witness whereof I have signed this specification.

DANIEL SMITH.
